HEATING SYSTEM FOR MOTOR DRIVEN CONVEYANCES

Charles E. Osborne, Chicago, Ill., assignor to
Stewart-Warner Corporation, Chicago, Ill., a
corporation of Virginia

Application December 12, 1936, Serial No. 115,477

6 Claims. (Cl. 237—12.3)

This invention relates to a heating system for motor driven conveyances having an internal combustion engine with a fuel pump and an intake manifold, and more particularly to that 5 class of heaters which utilize the fuel of the engine as the fuel for the primary heat producing element of the heating system.

The principal object of the invention is to provide highly efficient heater of the kind herein 10 described which is so designed and arranged to be installed that a circulation of heated fresh air is automatically induced into the tonneau of the conveyance, and an even predetermined temperature can automatically be maintained in the body 15 of the conveyance at all times.

According to my invention a primary heat producing unit is mounted on the dash in the interior of the body; and has one end of an air supply conduit connected therewith, the said air 20 conduit having its other end connected to an electric blower positioned on another part of the body. The intake to the blower is either from the interior or exterior of the conveyance body, depending on the temperature of the air in the body of the car. Two series of ports in the blower 25 intake are alternately opened and closed by a rotary valve which is thermostatically operated, so that when the air in the car is too hot the air will be drawn in from the exterior of the car and when the air in the car is too cold the air 30 will be drawn in from the interior of the car, and the blower will force the air over the primary heat producing element. As the thermostatic valve operates slowly the ports leading to the inside and outside of the body will both be 35 partly closed and partly opened so that the blower is drawing in both cold fresh air from the exterior of the body and heated air from the interior of the body. In this manner a supply of heated fresh air is supplied to the body of the car.

Among the special features incorporated in this heating system may be set forth the following.

1. A primary heat producing element which is 45 located in one position in the body and the air which is forced over the primary heater taken from any other part of the body or the extension of the body and thus a forced circulation of air is maintained throughout the body which is of a uniform temperature.

2. The thermostatic control which is set to 50 operate at a predetermined temperature at the blower intake assures a supply of fresh air to the body of the car and maintains it at a constant predetermined temperature automatically.

3. The primary heating element is a one-piece 55 iron casting comprising a pear shaped combustion chamber terminating in a series of U-shaped passageways for the combustion of the mixture supplied to the primary heating element by the

horizontal mixing valve. The fins cast to the U-shaped passageways and the pear shaped combustion chamber carry the heat therefrom.

4. An adjustable valve is positioned within the primary heating element to control the rate of 5 flow of the hot gases through the primary heating element.

5. A sight opening is provided in the combustion chamber so that it is possible to observe the 10 status of combustion to properly adjust the horizontal mixing valve which is screwed into one end of the primary heating element.

6. The primary heating element is suitably 15 mounted in a casing having a tubular support extending through a hole in the car body dash and rigidly secured thereto. Through this same 20 opening in the car body dash the tube, supplying the fuel leading from pressure side of the engine fuel pump extends to the mixing valve which furnishes the combustible mixture to the primary 25 heating element. The tube which connects the opposite end of the primary heating element and extends to the intake manifold of the engine also extends through the tubular support, and carries away the products of combustion. Thus a one hole mounting supports the heater and both the fuel supply and exhaust pass through the 30 opening.

7. The ignition vibrating type of coil which 35 energizes the spark plug is mounted within the heating element casing on an asbestos insulation panel and is thus protected from moisture. The casing has a front cover with a red jewel which is illuminated by the flame in the combustion chamber shining through the sight opening.

8. The casing of the heater has an air deflector 40 on each side and a pair at the bottom. The defectors at the sides can be opened to any position so that the air will be deflected downward or straight out from the side. The wings of the defectors on the sides encompass the primary heat producing element when the defectors are closed and have a right angle lip on their ends to prevent their being drawn entirely out. The two defectors at the bottom can be adjusted so as 45 to permit the air to be forced downward or toward the front seat of the automobile.

9. A switch on the front cover of the heater 50 which when thrown to the right turns both the electric connections to the spark plug and the electric blower and opens the fuel line leading to the mixing valve at the same time.

10. A pair of thermostatic bimetallic switches 55 positioned above the primary heating element and in close proximity thereto automatically connects the operation of the electric blower and also the ignition system of the primary heating element.

11. A primary heat producing unit which is of 60 small size, entirely automatic in its operation and one that can develop almost any degree of heat.

With the above objects in view, as well as others which will appear as the specification proceeds, this invention comprises the construction and arrangement of parts as now to be fully described, it being understood that the disclosure herein is merely illustrative, and in no way meant in a limiting sense, changes in details of construction and arrangements of parts being permissible as long as they are within the spirit of the invention and the scope of the claims which follow.

To describe my invention so that others versed in the art to which it pertains can make and use the same I have illustrated it on the accompanying three sheets of drawings, in which:

15 Figure 1 is a side view partly in section of a heater and electric blower constructed in accordance with my invention mounted on the dash of an automobile; Fig. 2 is a wiring diagram of the electrical circuits and thermostatic controls for 20 both the electric blower and the ignition for the parts shown in Fig. 1; Fig. 3 is a perspective view of the heater unit; Fig. 4, is a vertical cross sectional view of the heater unit taken on line 4-4 of Fig. 5; Fig. 5, is a vertical sectional view of 25 the heater unit taken on line 5-5 of Fig. 4; Fig. 6, is a perspective view partly in section showing the electric blower intake with the blower and motor broken away at the top; Fig. 7, is a detail sectional view showing the electric switch mounted in the upper part of the heater unit taken on line 7-7 of Fig. 8; Fig. 8, is a front elevation of the parts shown in Fig. 7, within the heater unit; Fig. 9, is a detail sectional view taken on line 9-9 of Fig. 8, and Fig. 10 is a detail 30 sectional view taken on line 10-10 of Fig. 8.

Referring to the drawings Figure 1 shows a general view of my improved heating system as applied to an automobile, the dash is shown at 11 and the upper horizontal portion of same is shown at 12. The primary heating unit 13 is rigidly secured on the inner side of the dash 11, see Figs. 1, 4 and 5 and is connected by a large tube extending through the dash and upward to a point above the top 12 where it is attached to 45 an inlet having openings above the top 12 and below the top 12.

The primary heating unit 13 is provided with a tubular extension 14 on the rear which extends through an opening provided therefor in the dash 11 and is rigidly secured to the dash by suitable bolts 15. A primary heating element 16 is rigidly secured in the unit 13 by the screws 17 which pass through the rear wall of the unit 13 and into suitable lugs provided on the element 16. The element 16 is a casting having a combustion chamber 18, see Figs. 4 and 5, which is of pear shape design and connecting with the small end is a tubular zigzag opening 19 having at its lower end a reduced opening provided with a valve 20 and beyond the valve is an opening which is screw threaded to receive a pipe 21. The lower end of the zigzag opening is provided with a screw plug 22 to close the hole left for removing the core of the casting. The pear 65 shaped combustion chamber 18 is provided with a screw threaded opening at one end into which is screwed the mixing valve 23 provided with the nozzle 24 the needle valve 25 the air inlets 26 the adjustable opening 27 and the valve 28. The 70 screw threaded end of the needle valve 25 is enclosed by a cap 30 provided with a gasket 29 to prevent any leakage.

The cast iron heating element 16 is provided with suitable cooling fins 31. A spark plug 32 is 75 provided in the pear shaped combustion chamber

18 for the purpose of igniting the combustible charge. The valve 20 in the tubular zigzag opening 19 has its operating stem concealed by the cap 33 which is screwed tightly against the gasket 34. As seen in Fig. 5 the front side of the pear shaped combustion chamber 18 is provided with a sight opening 35 provided with a glass closure 36 held in place by a suitable screw threaded cap 37 and gaskets 38. Above the glass closure 36 is a switch 39 also seen in Figures 7 to 10, inclusive, which has a pivotal shaft 40 having its bearing in the Bakelite bracket 41 rigidly secured to the asbestos plate 42 supported in proper position by having its ends slide into grooves 43 provided therefor on the inner sides 15 of the walls of the primary heating unit 13. The switch shaft 40 has rigidly secured to its inner end the contact arm 44 arranged to contact the screw 45 rigidly secured in the bracket 41 to make electrical connection therewith. Rigidly secured to the shaft 40 is an arm 46 which has its free end connected by a link 47 to the free end of an arm 48 rigidly secured to the stem of valve 28, see Figs. 4, 8 and 9. As best seen in Figure 8 the parts are so connected and arranged that when the switch 39 is in a vertical position the valve 28 will be in an open position and the contact arm 44 will be in contact with the screw 45. A fuel pipe 49 has one end rigidly connected to the mixing chamber 23 above valve 28, see 30 Figs. 4 and 9, and extends back of the heating element 16 where it extends out through the tubular extension 14 beside the pipe 21 extending from the lower end of the heating element 16; from whence said fuel pipe 49 connects with the 35 pressure side of the engine fuel pump, not shown.

Mounted rigidly upon the asbestos plate 42 is a vibrating coil 50 having one wire 51 connected to the spark plug 32 another wire 52 connected to ground and a third wire 53 connected to a binding post 54. The binding post 56 has a bimetallic thermostatic element 55 whose free end is normally in contact with the contact screw 54 which is rigidly secured in the asbestos plate 42, a wire 57 connects the binding screw 56 with the screw 45 at the switch 39. Also rigidly connected to the asbestos plate 42 is the binding screw 58 which is rigid with one end of a bimetallic thermostatic element 59 whose free end is normally out of contact with the binding screw 60, a wire 61 connects the binding screw 58 with the contact screw 45 at the switch 39. The asbestos plate 42 is provided with a depending ledge 62 to protect the two bimetallic thermostatic elements 55 and 59 from the cool air blown in through the tubular extension 14.

The front plate 63 of the primary heating unit 13 is made removable by taking out the screws 64, see Figs. 1, 3, 4 and 5. Below the switch lever 39 the front plate 63 is provided with a red jewel 65 registering with the glass closure 36. Obviously the switch lever 39 must be removed from the switch shaft 40 before the front plate 63 can be removed from the primary heating unit 13. Suitable hinged doors 66 are provided on the lower side of the heating unit 13. On each side of the primary heating unit 13 is a door 67 hinged at 68 provided with sides 69 which carry outwardly extending lugs 70 which take against the side walls of the unit 13 and thus prevent moving the doors 67 on their hinges 68 too far out. When adjusting the needle valve in the mixing chamber 23 the one door 67 is swung up out of the way on its hinge 68 by depressing the sides 69 enough to have the lugs 70 pass out

through the opening in the primary heating unit 13.

As above described the tubular extension 14 on the rear of the primary heating unit 13 passes through the dash 11 and the elbow 71 is attached to the protruding end of the extension 14 by means of a suitable screw 72. The elbow 71 is provided with suitable openings through which the pipes 21 and 49 extend, and the open end 10 of the elbow is connected to one end of a flexible conduit 73 whose other end is connected to the outlet port 74 of the blower 75 which is driven by motor 76. The inlet port to the blower 75 has two branches one branch on the exterior of the car body and one branch on the interior of the car body and each branch is provided with a valve which valves are preferably connected to operate in unison, i. e. the one valve is open when the other valve is closed and visa versa.

As seen in Figs. 1 and 6, where a preferred construction of fan intake is shown consisting of a tubular extension comprising the two tubular sections 77 and 78; the section 77 being secured to the upper and outside of the horizontal portion of the dash 12 and the section 78 being secured to the lower inner side of same. The upper section 77 is provided with a plurality of holes 79 and the lower section 78 is provided with a plurality of holes 80. Centrally disposed within the sections 77 and 78 is a shaft 81 having a bearing 82 at its upper end provided with a screw 83 whose end extends into a circular groove in shaft 81 to prevent the shaft having longitudinal movement. Another bearing 84 for the shaft 81 is provided near its lower end. The upper bearing 82 is supported in place by suitable arms 85 rigidly secured to the tubular section 77, and the lower bearing 84 is supported in place by the partition 86 rigidly secured to the tubular section 78. The lower end of the section 78 is closed by a cap 87 which is rigidly secured to the section 78. At a point between the partition 86 and the cap 87 is positioned a bimetallic thermostatic spiral element 88 having its inner end rigidly secured to shaft 81 at 89 and its outer end rigidly secured to the section 78 at 90 and as the temperature in the car increases or decreases the shaft 81 will be rotated in one direction or the other. A pair of tubular valves are rigidly secured to the shaft 81, the upper one 91 is positioned to co-operate with the holes 79 and the lower one 92 is positioned to co-operate with the holes 80, the number of holes in the valves 91 and 92 are the same as the number of holes in the sections 77 and 78. The necessary supporting arms extending from the shaft 81 to the valves 91 and 92 are made as small as possible so as not to interfere with the free flow of air drawn in by the blower 75. As seen in Fig. 6, when the holes 60 in valve 91 register with the holes 79, the holes in valve 92 do not register with the holes 80, and the rotating action of the valves 91 and 92 and of course also of the shaft 81, is limited by the end of the screw 93 taking against the stops 94 and 95 provided on the valve 92. The partition 86 as well as the cap 87 are provided with holes 96 to permit the free circulation of air from the interior of the car to the bimetallic thermostatic spiral element 88. To manually operate and retain the valve shaft 81 in either of its two positions a handle 97 is rigidly secured to the lower protruding end of shaft 81 and a suitable hook or lever 98, see Fig. 1, is pivoted to the cap 87 to hold the handle 97 in either of its two positions.

Referring to Figs. 1 and 4, a wire 99 connects

the binding screw 60 to the blower motor 76 from whence a wire 100 connects with ground. The pipe 21 leading from the heater unit 16 to the manifold of the engine, not shown, is provided with a shut-off valve 101 and the fuel pipe 49 is provided with a valve 102 which may be closed when the heater is not used.

In Fig. 2 is shown the electric circuits employed to carry out my invention and in which the source of electric power or the battery 103 10 is connected on one side with ground and on the other side with the ammeter 104 through wire 105 with switch 44; from the switch 44 when contact is made with the screw 45 the current passes through wire 51, bimetallic element 5, wire 53, 15 vibrating coil 50 and thence to ground through wire 52. The other circuit from the coil 50 passes through wire 51, spark plug 32 and thence to ground. The other circuit when switch 44 is closed passes from the screw 45 through wire 61, binding screw 58, bimetallic element 59, contact 60, wire 99, motor 76 and thence through wire 100 to ground.

In operation, the parts being connected to the automobile substantially as shown in Fig. 1, the mixing valve having been properly adjusted by viewing the same through the closure glass 36 and the valve 20 having been properly adjusted, the engine or motor on the car is started. The operation of the engine immediately tends to force fuel through pipe 49 to the mixing valve 23 where the combustible mixture is discharged into the combustion chamber and the intake manifold causes a suction through pipe 21 from the exit end of the combustion chamber zigzag tubes or openings 19. However the heater unit will not come into operation until the switch 39 is moved to the right to a vertical position as seen in Figs. 1, 3, 5, 7 and 8; which movement will make the electrical connection between switch 40 arm 44 and the contact screw 45 and will also open the valve 28 permitting the fuel to be forced through the mixing valve 23 and into the combustion chamber 18. The bimetallic thermostatic switch 55 being closed, see Figs. 2 and 4, the spark plug 32 will be energized to ignite the fuel in the combustion chamber 18. The bimetallic thermostatic switch 59 being open the blower motor 76 will not operate. The products of combustion will pass from the combustion chamber 18 through the zigzag openings 19, through valve 20 thence through tube 21 to the intake manifold of the engine, thus heating the primary heating element 16. When said primary heating element 16 becomes sufficiently hot the bimetallic thermostatic switch 59 will close, the blower motor 76 will operate and the blower 75 will force air through the flexible conduit 73, elbow 71, tubular extension 14 and over the primary heating element 16. Also the bimetallic thermostatic switch 60 55 will open and the spark plug 32 will not be energized, but the combustion chamber 18 will be sufficiently hot to ignite the charge. The operator will adjust the doors 66 and 67 as desired. The blower 75 will draw the air in through the 63 intake from outside the body through openings 79 or from inside the body through openings 80. When the temperature inside of the car has reached the predetermined degree the spiral bimetallic thermostatic element 88 will turn the 70 shaft 81 and the valves 91 and 92 to the proper position to retain the temperature in the car at the said predetermined temperature, which will be in a position to draw some air from outside the car and some from inside the car.

Should any passenger in the car desire to have the temperature in the car lowered the handle 97 can be moved to the left manually, as seen in Fig. 1, and secured in such position by swinging 5 the hook 98 down over same to hold it in said position to draw the cool air from outside the car through the holes 79; and if the temperature inside the car is desired to be warmer then the handle 97 is moved manually to the right, as 10 seen in Fig. 1, and secured in such position by swinging down the hook 98 so that the air will be drawn in through the holes 80 from within the car.

From the above description it will be understood 15 that this heating system is entirely automatic in operating and the heat is supplied by a primary heat producing element so that no dependence is placed on the exhaust from the engine or water circulating in the engine water jacket. With this system of heating a car there is no danger of engine exhaust gases entering the car and the heat is generated to a high temperature although the engine may be idling. The heat in the car is automatically maintained at a predetermined temperature and an ample amount of fresh air is supplied to the interior of the car which is of great importance to the passengers in a closed car, and furthermore such fresh air is supplied to the interior of the car without opening any windows. Another great advantage of this heating system is that the drawing in of fresh air from the outside and heating the same before it is delivered to the interior of the car will prevent the accumulation of moisture on the windows thus permitting the driver unobscured vision and thereby preventing accidents. Another advantage gained by this heating system is that the car radio will in no way be interfered with because after the heating system is in operation the spark plug circuit is broken so that the vibrating coil 50 is cut out of service. From the above description it will be noted that the blower 75 will not come into operation until the heater unit is sufficiently hot to heat the air, and no cold air is blown on the occupants of the car. Another advantageous feature of this heating system is that the coil box 50 is located within the confines of the primary heating unit 13 and no moisture can get to the said coil box.

Having thus fully described my invention what I desire to secure by Letters Patent of the United States is:

1. In a device of the class described, a heat producing element, an electric spark plug for igniting the fuel in said heat producing element, an electric circuit for said spark plug including a bimetallic thermostatic switch, an electric motor for driving a blower to force air over said heat producing element, an electric circuit including a bimetallic thermostatic switch for said motor and means whereby the said two bimetallic thermostatic switches will be heated by the said producing element and when said switches are heated to a predetermined temperature the electric circuit leading to the spark plug will be broken and the electric circuit leading to the motor will be completed.

2. In a device of the class described, a fuel consuming heating unit enclosed in a suitable case provided with a tubular air intake extension projecting through a hole in the dash of an automobile and serving as the sole support of the said heating unit, a fuel pipe for conveying fuel

to the said heating unit extending through said tubular extension and a pipe to carry away the burnt gases from said heating unit extending through said tubular extension.

3. In a device of the class described, an internal combustion engine with an intake manifold and a fuel pump, a primary heat producing unit positioned within the body of the conveyance to be heated, a horizontal mixing valve having a fuel shut-off cock for mixing air and fuel connected 10 to the inlet of the unit, a pipe connecting the pressure side of the engine fuel line with the said mixing valve, a controlled valve in the primary heat producing unit controlling the flow from the heat producing unit to the intake manifold, a pipe leading from the outlet of the unit to the intake manifold of the engine, a housing enclosing the unit provided with a single tubular support extending through the dash of the conveyance and secured thereto, an electric suction 20 blower mounted on the opposite side of the dash and operatively connected with said tubular support to force air over the primary heat producing unit, a spark plug mounted in said unit, a vibrating ignition coil mounted in said housing 25 and operatively connected with the spark plug, a source of electricity, an electric circuit including said source, said electric blower and said ignition coil, a switch in said circuit and suitable connections between said switch and said shut-off cock whereby both will be operated in unison.

4. In a device of the class described, a heat producing element, an electric spark plug for igniting the fuel in said heat producing element, an electric circuit for said spark plug including 35 a bimetallic thermostatic switch, means whereby the said bimetallic thermostatic switch will be heated by the said heat producing element and the electric circuit will be broken and the fuel will be ignited by the heat within said heat producing element an air circulating means for rapidly cooling said bi-metallic switch when said heat within said heat producing element is insufficient to ignite the fuel.

5. In a device of the class described, a primary heat producing element comprising a pear-shaped combustion chamber having its exit end terminating in a zigzag shape tube and provided with a plurality of cooling fins, suitable housing enclosing said unit provided with side air deflectors having side wings to encompass said unit, and a mixing valve introducing combustible elements into said combustion chamber located inside of said housing and exposed to heat developed in said chamber.

6. In combination with a motor vehicle having a blower and a heating unit located in the path of the exhaust from said blower for supplying the interior of said motor vehicle with heated air, of an inlet passageway for said blower extending through the dash of said vehicle and having two inlet openings in the side thereof and a restricted opening at the end thereof, one of said side openings being exposed to the atmosphere outside of the motor vehicle and the other of said side openings and the end opening being exposed to the air inside said motor vehicle, a valve for determining the proportion of air received through said side openings, a temperature responsive means mounted in said passageway and exposed to the air flow through said end opening for controlling said valve.
